APPARATUS FOR MAKING COMBS

Joseph S. Wilcox, Athol, Mass., assignor to The Wilcox Company, Athol, Mass., a corporation of Massachusetts

Application December 12, 1932, Serial No. 646,856

1 Claim. (Cl. 18—3)

This invention relates to an improved apparatus for making celluloid combs.

It is the general object of my invention to provide an apparatus by which a superior celluloid comb may be manufactured at a substantial saving of time and labor and consequently at a reduced cost.

My invention further relates to arrangements and combinations of parts which will be herein-
10 after described and more particularly pointed out in the appended claim.

My improved apparatus for carrying out cer-
tain steps thereof, is shown in the drawings, in
which

15 Fig. 1 is a plan view of a piece of sheet celluloid slotted to provide two comb blanks;

Fig. 2 is a side view thereof;

Fig. 3 is a plan view of a comb blank after separation;

20 Fig. 4 is a partial plan view showing the end teeth in corrected position;

Fig. 5 is a partial side elevation of the comb blank, looking in the direction of the arrow 5 in Fig. 4;

25 Fig. 6 is a front elevation of a pair of forming dies preferably used in carrying out my improved method;

Fig. 7 is an end view thereof, looking in the direction of the arrow 7 in Fig. 6;

30 Fig. 8 is a sectional plan view, taken along the line 8—8 in Fig. 6;

Fig. 9 is a sectional bottom view, taken along the line 9—9 in Fig. 6;

35 Fig. 10 is a partial sectional plan view, similar to Fig. 8 but showing a comb blank positioned in the lower die;

Fig. 11 is a partial sectional end elevation, taken along the line 11—11 in Fig. 6 but with a comb blank in position;

40 Fig. 12 is a view similar to Fig. 11 but with the dies closed on the comb blank;

Figs. 13 and 14 are detail longitudinal sectional elevations, taken along the lines 13—13 in Fig. 11 and 14—14 in Fig. 12 respectively, and

45 Fig. 15 is a plan view of a portion of a comb after removal from the forming dies.

Referring to Figs. 1 to 5, I first take a piece of sheet celluloid S of a desired thickness and form a plurality of slits 17 therein, preferably by
50 use of a special slitting machine which, however, forms no part of my present invention.

After the sheet S has been thus provided with the slits 17, the two parts of the sheet are sepa-
rated along the lines of the slits, thus providing

55 two comb blanks B from each slitted sheet S,

These blanks B have the general outline of the finished comb, with the exception that one end tooth 18 of each blank is widely spaced from its adjacent comb tooth 19, as indicated at the left in Fig. 3.

Having thus prepared the blank B, the first necessary step is to soften the end tooth 18 by the application of heat thereto and to bend the tooth 18 to the aligned position indicated in Figs. 4 and 5, with the tooth 18 properly spaced and located with respect to the next adjacent tooth 19. The blank B is then placed in a pair of forming dies illustrated in detail in Figs. 6 to 14 inclusive.

These dies comprise fixed and movable die 15 members 20 and 21 (Figs. 6 and 7) mounted on relatively heavy die supports 22 and 23. Guide studs 25 are mounted in the lower die support 22 and these studs are a sliding fit in aligned openings 26 in the upper die support 23.

The lower die member 20 is preferably pro-
vided with a raised portion 30 (Figs. 7 and 8) in
which a plurality of tooth recesses 31 (Figs. 8
and 13) are formed. The upper die member 21
is similarly provided with a downwardly project-
ing portion 32 having a plurality of tooth re-
cesses 33 (Figs. 9 and 13). A guide-bar 35 (Fig.
7) is secured to the lower die member 20 and aids
in locating the back edge of the comb blank B
when the blank is inserted as indicated in Figs. 30
10 and 11.

Pairs of spacing pins 40 (Figs. 8 and 13) are
located between each two adjacent tooth re-
cesses 31, and additional end positioning pins 41
(Fig. 8) are mounted at the ends of the member
20. Openings 42 (Figs. 9 and 13) are provided
in the upper die member 21 in alignment with
the pins 40 and 41 and loosely receive these pins
when the dies are closed.

The tooth recesses 31 and 33 are rounded at
the bottom and top respectively as clearly shown
in Figs. 13 and 14 and are also rounded at the
ends of the recesses as shown in Figs. 8 and 9.
Furthermore, the edges of the raised portions 30
and 32 are beveled along the side nearer to the
guide-bar 35 as indicated at 45 in Fig. 7.

Having provided dies constructed as above de-
scribed and having prepared a comb blank as in-
dicated in Figs. 3 to 5, the blank B is then placed
on the lower die 20 as indicated in Figs. 10 and 50
11, with the back edge of the blank abutting the
guide-bar 35 and with the teeth of the blank
positioned by the pairs of pins 40 and the end
pins 41.

When the teeth are thus located, they are in 55

the desired spaced relation which they will occupy in the finished product. Before thus positioning the comb blank B, the blank is heated to a temperature high enough to substantially 5 soften the celluloid material.

5 After the heated blank B is thus positioned, the upper die member 21 is moved downward and is caused to apply substantial pressure to the blank B, causing the teeth 18 and 19 to be forced 10 into the tooth recesses 31 and 33 and to be simultaneously changed from the rectangular cross section of Figs. 3 to 5 to the substantially rounded or elliptical cross section of Figs. 14 and 15.

10 As the dies 20 and 21 are unheated, the blank B quickly cools after being forced into the tooth recesses 31 and 33, after which the blank is removed for polishing or other desired finishing 15 operations.

15 It will be noted that the comb teeth 18 and 19 are not only rounded in cross section by the forming operation, but that the ends of the teeth are also rounded and pointed and that the edge of the comb back is beveled between the teeth as indicated at 50 in Fig. 15.

25 I am thus able to completely form and point

the teeth of a celluloid comb direct from the slotted blank by the simple process of heating the blank and pressing the blank between the dies 20 and 21, which dies are themselves preferably 5 in an unheated condition. A celluloid comb of superior grade and with carefully shaped and pointed teeth can be thus produced at a substantial saving in time and labor as compared with the best previous practice.

Having thus described my invention and the 10 advantages thereof, I do not wish to be limited to the details herein disclosed, otherwise than as set forth in the claim, but what I claim is:—

Apparatus for making a comb comprising a 15 pair of dies having tooth recesses therein separated by intervening raised portions and a plurality of tooth-locating pins in one die positioned in said intervening raised portions and effective to hold the previously separated teeth of a comb blank in predetermined spaced positions prior to 20 and during the application of the second die thereto, and said second die having corresponding openings in its intervening raised portions to receive said pins as said dies approach each other.

JOSEPH S. WILCOX. 25
